UNITED STATES PATENT OFFICE.

DANIEL JOSEPH CONNELL, OF BUTTE, MONTANA.

DRAIN-COVER.

1,169,010.

Specification of Letters Patent. Patented Jan. 18, 1916.

Application filed November 18, 1915. Serial No. 62,167.

To all whom it may concern:

Be it known that I, DANIEL J. CONNELL, a citizen of the United States, and a resident of Butte, in the county of Silverbow and 5 State of Montana, have invented certain new and useful Improvements in Drain-Covers, of which the following is a specification.

My invention relates to drains, as in kitchen sinks, and the main object thereof 10 is to provide a readily applied and as readily removable cover therefor which will enable a housewife to use the sink for washing dishes, clothes, and the like, and avoid the necessity for using an unsatisfactory dish-pan, or for carrying sufficient hot water to a 15 wash-tub to use the latter, and a further object is to provide such a device which is simple though highly efficient in use, which is held in operative position against the like- 20 lihood of displacement in the use of the sink, which will not present any surface obstructions whereby dishes might be broken or chipped, and which is comparatively inex- 25 pensive.

My invention is fully described in the following specification, of which the accompanying drawings form a part, in which like characters refer to like parts in each of the views, and in which:—

30 Figure 1 is a sectional view taken through the drain of a conventional sink such as used in the kitchens of dwellings, showing my invention in operative position and also in section; Fig. 2 is a top plan view of my in- 35 vention removed from the sink; and Fig. 3 is a bottom plan view thereof.

In the drawings forming a part of this application I have shown a metal disk 4 provided with two radial grooves 5 in its 40 upper surface forming a handle or finger-piece 6 at the center of said disk and within which is clamped the head 7 of a pin 8 projecting downwardly from said disk, and I also provide a ring 9 on the under side of 45 said disk at the edge thereof.

In Fig. 1 I have shown my invention applied to a sink 10 provided with the usual drain 11 covered by a conventional strainer 12 having a plurality of holes therethrough 50 and with the central one of which, 13, my invention is connected.

The disk 4 is made sufficiently thin to not present any material obstruction at the edge thereof with respect to the bottom surface of the sink, and the handle 6 is flush with the 55 upper surface of the disk 4 so as not to injure dishes being washed in the sink, the drawing being slightly exaggerated with respect to the thickness of the disk for clearness of illustration.

With my drain cover in position the sink may be filled, or partially filled, with water and used instead of a dish-pan or tub, no likelihood of displacement occurring in the use of the sink by the dishes engaging any 65 part of my cover or, if clothes are being washed, of the clothes catching on the cover, whereby injury to the articles being washed might occur, or whereby leakage of water from the sink might result.

70 My invention is very simple and may be made of galvanized metal, or of nickel-plated metal, according to the grade and selling price thereof, but it will be understood that I do not desire to limit myself 75 to any specific material or finish.

When the use of the cover is not desired all that is necessary is to grasp the handle 6 between the thumb and finger of one hand and withdraw the pin 8 from the hole 13 80 and, while the cover is in use, the suction in the drain and the weight of water in the sink serve to hold the cover firmly against the strainer 12.

Having fully described my invention, 85 what I claim as new, and desire to secure by Letters Patent, is:—

In a cover for a sink drain, a metal disk provided with radial grooves in its upper surface forming a handle, a headed pin em- 90 bedded in said handle and projecting downwardly from said disk, and a resilient ring around the edge of said disk at the under side thereof.

In testimony whereof I have signed my 95 name to this specification in the presence of two subscribing witnesses.

DANIEL JOSEPH CONNELL.
